**GUIDING DEVICE FOR THE VANE ASSEMBLIES
OF A FLUID HANDLING DEVICE**Karl Eickmann, 2420 Isshiki, Hayama-machi,
Kanagawa-ken, JapanOriginal application Dec. 5, 1963, Ser. No. 328,395, now
Patent No. 3,320,898, dated May 23, 1967. Divided and
this application May 22, 1967, Ser. No. 640,108
15 Claims. (Cl. 103—136)**ABSTRACT OF THE DISCLOSURE**

The vane assemblies of a fluid handling device have turnable control pins with end portions axially projecting from the other parts of the respective vane assembly and guided along endless guide tracks matching the outline of an endless inner casing face along which the radially outer parts of the vane assemblies move during rotation of the rotor in which the vane assemblies are mounted.

Reference to a related application

The present application is a divisional application of the copending application Ser. No. 328,395, now U.S. Patent 3,320,898.

Background of the invention

It is known to provide fluid handling machines with guide means radially inward of the vanes for forcing the vanes outward during rotation of the rotor in which the vanes are mounted. In accordance with the prior art, only machines whose rotors have no radially projecting end walls are provided with such guide means. This type of machine is not capable of working at high power and efficiency because the vanes have the tendency to be deformed by high pressure which causes leakage losses.

On the other hand, vane machines according to my earlier patents, for example U.S. Patent 2,975,716, are capable of operating at high power and efficiency, because the rotors thereof have end walls and slots in the center rotor portion as well as in the end walls for guiding the vanes.

In fluid handling machines of the type disclosed in my earlier Patent 2,975,716, it is not possible to provide guide means for guiding the vanes for outward movement in the slots of the rotor. This is due to the fact that especially at low speed of the rotor, the vane assemblies are not pressed tightly enough against the inner endless face of the casing member so that a tight seal between the intervane spaces could not be obtained. As a result, machines of this type do not smoothly start.

Summary of the invention

It is the main object of the present invention to overcome this disadvantage of high power fluid handling devices, and to provide a fluid handling machine of the type having vane end portions guided in end members of the rotor, with control means by which the vanes are urged outward.

Another object of the invention is to use a pivot pin provided in a vane assembly as disclosed in my prior Patent 3,158,103 for cooperation with guide tracks by which the vane assemblies are urged outwardly.

In accordance with one embodiment of the invention, each vane assembly is composed of a plurality of vane parts including a control part, such as a pivot pin, whose end portions are located outwardly of non-circular guide tracks sliding on the same so that the vane assemblies are moved outwardly along the endless inner face of a casing

2

member by which the inward movement of the vane assemblies is accomplished.

The endless guide tracks are either provided on the casing means, or on guide portions supported by a non-circular shaft which passes through a central bore in the rotor, and has an end portion secured to the stationary casing means of the machine.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

Brief description of the drawing

FIG. 1 is an axial sectional view taken on line I—I in FIGS. 2 and 3, and illustrating a first embodiment of the invention;

FIG. 2 is a cross-sectional view taken on line II—II in FIG. 1;

FIG. 3 is a cross-sectional view taken on line III—III in FIG. 1;

FIG. 4 is an axial sectional view taken on line IV—IV in FIG. 5 and illustrating a second embodiment of the invention;

FIG. 5 is a cross-sectional view taken on line V—V in FIG. 4; and

FIG. 5B is an enlarged cross-section illustrating a detail of FIG. 5 within the circle BB in FIG. 5.

Description of the preferred embodiments

Referring first to the embodiment of FIGS. 1 to 3, an outer stator casing means includes two parts 601A and 601 and supports a casing member 608 having an endless inner non-circular face 612 and being provided with a fluid inlet 679 and a fluid outlet 680. Rotor means are mounted in bearings of the casing means and including a shaft portion 622, a center rotor portion 602 and radially outwardly projecting end members which embrace lateral end faces of the casing member 608 and form with the same and the rotor center portion 602, a working space which is divided into intervane spaces by vane assemblies mounted in radial slots 657 extending into the end members of the rotor. Vane assemblies are respectively mounted in the slots of the rotor means for radial movement, each vane assembly including an inner part guided in the respective slot, a pivot pin 610, and a shoe 611 pivotally mounted on pivot pin 610 and sliding on the inner endless face 612 in sealing contact.

The device illustrated in FIGS. 1 to 3 is preferably a combustion engine to which a fuel-and-air mixture is supplied through the inlet port 679 to enter the intervane spaces 625A or 625B. The fuel-air mixture is compressed when the respective intervane space reaches the position 625C. Compression continues when the intervane space reaches position 625D. In the position of the intervane spaces 625D in FIG. 2, or 625E in FIG. 3, the compression is so great that the fuel-air mixture is heated to a temperature higher than its ignition temperature so that the fuel-air mixture starts combustion without the aid of additional ignition means.

After the intervane space has reached the position 625E, expansion of the intervane space takes place due to the expansion of the combustion gases, and is continued until the intervane spaces pass through positions 625F and 625G whereupon the burnt gases are discharged from intervane space 625H through outlet port 680.

As shown in FIG. 2, the casing 608 is divided into two casing parts 608A and 608B along the dividing plane AB

also designated by reference character 608AB. The casing parts 608A and 608B are fastened together by bolt means 648A, 648B, 648C and 648D. Casing part 608A contains the inlet port 679, and casing part 608B contains the outlet port 680. The outer casing means surrounds the inner casing member 608 and is fastened to the same by bolt means 648E and 648F.

Casing cooling spaces 671 are provided in casing member 608, and are surrounded or closed by the outer casing 601. Casing seals 601A and 601B are provided for sealing the cooling space 671 between casing 601 and casing member 608. Casing ribs 676 for transferring heat extend into the cooling space 671.

Beds 637, seats 638, seats 639, spring means 651, outer beds 633, inner beds 632, outer seals 634, inner seals 635, casing covers 631 and sealing faces 688 are provided for sealing the working space. Support rings 604A and 604B are provided and held in place by snap rings. The rotor means include a central rotor part 602, rotor end members 604 and 605 with inner annular faces 613 and 614 which are in sliding engagement with the lateral faces of inner casing member 608.

The vane assemblies 609, or vane parts 643 and 644 are provided with seals 645 inserted into the respective seal beds 645A. The seal beds 645A extend over the whole length of the center part of the vane and also extend to the axial vane end portions 615 and 616 which are located in slot portions of the end members of the rotor and have radial extensions 619 and 620. Vane seal 645 is provided with seal faces 645B or 645C. Due to the effective sealing of vane seals 645, leakage between the intervane spaces is prevented.

In accordance with the invention, non-circular endless guide tracks 47 are provided on the parts 601A and 601B of the outer casing 601 for guiding slide members 46, best seen in FIG. 1 which are turnably mounted on the end portions of pivot pin 610. Pivot pin 610 and the slide members 46 are a control part of the vane assembly by which the vane assembly is moved outwardly due to the outline of the guide tracks 47. Since slide members 46 are turnable on the end portions of pins 611, they follow the contour of the guide tracks 47. Axial separation of slide members 46 from pins 611 is prevented by the sliding abutment of the axial end face of the slide members 46 on an enless face 47A of the respective casing part 601A or 601B.

During rotation of the rotor, slide members 46 slide along the guide tracks 47, or roll along the same if members 46 are constructed as rollers having bores 46A for receiving the end portions of pins 610. The guide tracks 47 have such a configuration that the control part 610, 46 of the vane assembly 609, 643, 644, 610, or 611 are forced to move outward in radial direction so that the shoe 690 of the respective vane assembly slides along the inner casing face 612 in tight sealing engagement. When the shoes 690 move along portions of the endless inner face 612 where the intervane spaces are reduced in size, the vane assemblies are moved inwardly by the inner endless face 612. The action of the guide tracks 47 prevents the sticking of the vane assemblies in the respective slots during expansion of the intervane spaces. Such sticking of the vane assemblies may happen due to deformation of a vane part or the rotor slot, or due to friction of the sealing means. Evidently, the follower parts 46 could be constructed not only as slide or rollers, but also as ball or roller bearings.

Guide tracks 47B are provided outwardly of guide tracks 47 for guiding slide members 46 inwardly together with the vane assembly, as shown in FIG 1, and also in FIG. 2 in broken lines. Guide tracks 47B perform the function of the inner endless face 612 for urging the vane assemblies inwardly during the contraction of the intervane spaces, but may be omitted.

The function of outer endless guide tracks 47B is to prevent too great pressure of slide shoe 611 against the

inner face 612 of casing member 608. Guide tracks 47B can be designed so that a certain clearance remains between the outer face 690 of shoe 611 and the endless inner face 612 whereby friction is reduced. Sealing means 692 of little weight may be provided in slide shoe 611 for sealing the clearance between the outer face 690 and the inner endless face 612.

From the above description of FIGS. 1 to 3 it becomes apparent that the present invention provides each vane assembly with a control part 610, 46 which is guided by guide track means 47, 47A, 47B for moving the outer parts of the vane assemblies along the inner endless face 612 of casing member 608 which forms the intervane spaces with the vanes and the rotor.

Referring now to the embodiment illustrated in FIGS. 4, 5 and 5B, which illustrates a double acting rotary pump or motor, the casing means 1001A is integral with the casing member 1008 which has an inner endless face 1012. The casing is divided along radial planes into a plurality of parts, for example into two casing halves 1001E and 1001F. The casing parts 1001E and 1001F are bolted together by bolt and nut means 1048.

The dividing face is schematically indicated at 1001G, and it is evident that the casing may be divided in more than two parts.

Casing covers 1001B and 1001C are parts of the composite casing 1001A. The rotor 1002 of the machine has a shaft 1062 which may be sealed by sealing means 1063. The rotor has a center part 1002 and end walls 1004 and 1005 on which lateral cover parts 1006 and 1007 abut. Cover rings 1006A and 1007A surround the side walls 1004 and 1005. The side walls, covers, and rings constitute end members of the rotor which project from the center portion of the rotor outwardly in axial direction.

Radial slots 1057 are formed in the rotor center part 1002 and extend into the side walls 1004 and 1005 where they are closed at the axial ends by covers 1006 and 1007 and at the radially outer ends by rings 1006A and 1007B. Rings 1006A and 1007A are in sliding engagement with the lateral end faces of casing member 1008 and form with the same and the vane assemblies sealed intervane spaces.

The division of the end members into covers 1006, 1007, rings 1006A, 1007A and side walls 1004 and 1005 considerably facilitates the manufacturing and assembly of the apparatus.

Rings 1006A and 1007A may be used for limiting outward movement of the vanes so that the clearance between the outer face 1090 of slide shoe 1011 and the endless inner face 1012 of casing member 1008 can be exactly determined. The inner diameter of the rings 1006A and 1007A can be selected that due to the deformation produced by the pressure, the vanes may move radially outwardly farther if the rings are deformed so that the clearance between the outer face 1090 of the slide shoe and the respective portion of the endless inner face 1012 decreases when the pressure in the respective slots increases.

The clearance and corresponding leakage losses are thereby reduced.

Rotor center portion 1002 has radial slots 1057 and rotor side walls 1004 and 1005 have slot extensions 1058 and 1059.

A vane means 1009 is slidably mounted in each slot and has a pivot pin 1010 supporting the respective slide shoe 1011 for angular movement. Intervane spaces are formed by the vanes 1009 in the working space bounded by the inner face 1012, rotor side walls 1004, 1005, and rotor center portion 1002. The intervane spaces 1025 have positions 1025A to 1025F. The endless inner face 1012 of the casing member 1008 is non-circular and has such a configuration that during rotation of the rotor, each intervane space 1025 on the left of the dividing plane 1001G increases its volume to a maximum, and thereafter reduces

its volume to a minimum. The increase and decrease of the volume of the intervane spaces is used for sucking in and discharging the fluid through entrance port 1053 and discharge port 1054.

In accordance with the invention, each vane assembly 1009, 1010, 1011 is controlled to move outwardly so that the faces 1090 are in any angular position of the rotor in sliding engagement with the inner casing face 1012.

Each end member, and more particularly each end wall 1004 and 1005 has a radial recess 1004A and 1005A projecting outwardly from the inner central bore of the rotor. Covers 1006 and 1007 close recesses 1004A and 1005A in axial direction.

Guide means 1046A and 1046B are located in each of recesses 1004A, 1005A. Guide means 1046A and 1046B have endless guide tracks 1047A and 1047B. The outline of the guide tracks corresponds to the outline of the endless inner face of casing member 1008. In accordance with the invention, the inner endless face 1012 of the embodiment of FIG. 4, and the inner endless face 612 of the embodiment of FIG. 1 are composed of part-circular face portions which considerably facilitates the manufacturing of the machine. The guide tracks 1047A, 1047B, and 47, respectively, are composed of corresponding part circular track portions matching the portions of the endless inner face 612 or 1012 in radius and angular positions.

As best seen in FIG. 5, guide member 1046 extends radially outwardly to the area where the respective intervane space has its greatest volume, and the respective guide member 1046 has a lower track portion in radial direction where the intervane space will have a smaller volume. As viewed in the cross section of FIG. 5, the guide members project to the right and to the left farthest in radial direction, and are narrower in the direction of the plane 1001G. This is due to the fact that the greatest volume of the intervane spaces is assumed in a horizontal plane, and the smallest volume is assumed in a vertical plane.

The dimensions and configuration of the guide members and of the guide tracks 1047A, 1047B must be very accurately observed during manufacture in order to guide and push the vanes 1009 in radial outward direction to a position cooperating with the endless inner face 1012 of the casing member 1008. If the accuracy is insufficient, a clearance causing excessive leakage losses would appear between the outer slide face 1090 of vane part 1011 and the endless inner face 1012.

FIG. 5 shows different constructions for alternate vane means. One vane means has an outer shoe 1090 mounted for pivotal movement by means of a pivot pin 1010 on the vane part 1009 which has at the inner end a radial recess receiving a vane portion 1000C with an open bearing recess in which a control pin 1009D is mounted for angular movement. Springs 1051 in recess 1009B abut vane parts 1009 and 1009C to urge control pin 1009D inward so that the end portions of the control pin abut the guide tracks 1047A and 1047B. The construction of the alternate vanes is substantially the same, but instead of the shoe 1090, two pins 1011X and 1011Y are provided at the outer end of the vane part 1009Z, as also shown in FIG. 5B. Slide pins 1011X and 1011Y have flat slide faces 1090' sliding on the inner surface 1012. A small chamber 1011G is formed between the slide pins 1011X and 1011Y, each of which is capable of turning the angle alpha for following the curvature of the endless inner face 1012 of casing member 1008.

In both vane constructions, the control part 1009D slides on the guide tracks 1047A, 1047B for moving the vane outward and into contact with the inner face 1012. Due to the fact that the end portions of control part 1009D slide on the guide tracks, they transmit a force tending to rotate guide members 1046A, 1046B. Therefore, guide members 1046A, 1046B must be mounted within the turning motor in such a manner that they

cannot rotate due to engagement by the control part and also by lateral faces of rotor end walls 1004, 1005 and rotor covers 1006 and 1007.

In accordance with the invention, stationary mounting means are provided in the central bore of the rotor. The mounting means includes a shaft having a thick portion 1046D, and a thin portion 1046D'. Portion 1046D is secured to a portion of the stator casing and prevented by a pin 1001Z from turning movement. The thin shaft portion passes through central openings in guide members 1046A and 1046B and ends in the region of the end cover 1007. The shaft portion 1046D' has two flat faces 1046E and 1046F, and the inner openings of the guide members have a corresponding slot-shape to fit on the faces 1046E and 1046F whereby turning movement of the guide members is prevented, and the same are securely mounted within the radial recesses 1004A and 1005A of the rotor.

It is evident that any other non-circular shape of the mounting shaft, or a splined mounting shaft would accomplish the same purpose. The rotor is mounted by means of shaft 1062 in the bearing portion 1063 of the outer casing, and also by means of a hub portion of end cover 1006 on the mounting shaft portion 1046D. The vane parts 1009Z have radial projections 1015 and 1016 at the axial ends thereof which partly embrace the casing member 1008, as best seen in FIG. 4. In this manner axial guidance of the vanes is obtained. Due to the fact that the control parts 1009D, 1009C can move into and out of the recesses 1009B while engaging the guide tracks 1047A, 1047B, a sliding of slide pins 1011X and 1011Y on the endless inner face 012 is assured. Members 1011X, 1011Y perform an angular movement in the corresponding grooves of vane part 1009Z while sliding along portions of different curvature of the inner endless face 1012.

Control pin 1009D may slide on the guide tracks, but could be provided with rollers or slide blocks turnably mounted on control pin 1009D, as described with reference to FIG. 1. Spring means 1051 compensate small inaccuracies between the outline of the guide tracks and of the endless inner casing face 1012. The inward travel of the vanes is obtained by the configuration of the endless inner face 1012 in the regions where the intervane spaces are reduced in volume.

It will be understood that each of the elements described above may also find a useful application in other types of fluid handling machines differing from the type described above.

While the invention has been illustrated and described as embodied in a guiding device for vane assemblies, it is not intended to be limited to the illustrated embodiments, since various modification and structural changes may be made without departing from the spirit of the invention.

What is claimed as new and desired to be secured by Letters Patent is set forth in the appended claims.

I claim:

1. In a fluid handling device, in combination, casing means including a casing member having a non-circular endless inner face and lateral end faces and inlet and outlet means for a fluid; rotor means mounted in said casing means for rotation about an axis, and including a central rotor portion located within said endless inner face and two end members projecting in radial direction from said central rotor portion and having a greater diameter than the same and said endless inner face, said end members having endless lateral peripheral faces being, respectively, located opposite at least portions of said lateral end faces embracing the same in sliding and sealing contact whereby a working chamber for said fluid is formed between said rotor means and said endless inner face of said casing member, said rotor means being formed with a set of slots located in radial planes and extending in axial direction in said central rotor portion and into said end members; a set of vane assemblies respectively mounted in said slots for radial movement

into and out of said slots for dividing said working chamber into a set of intervane spaces sealed from each other, each vane assembly being composed of a plurality of vane parts aligned in radial direction and including a control part; and guide means supported on said casing means and having non-circular guide track means whose outline matches the outline of said endless inner face, said guide track means being disposed radially inward of said control part and guiding the same and said vane means in outer radial direction during rotation of said rotor means so that said vane assemblies move along said endless inner face.

2. A device as claimed in claim 1 wherein said control part includes a pin having axially projecting end portions, and wherein said guide means include two non-circular endless guide tracks respectively located radially inwards of said end portions in sliding contact with the same for guiding said pins and said vane assemblies.

3. A device as claimed in claim 1 wherein said control part includes a pin having axially projecting end portions, and slide members mounted for turning movement on said end portions; and wherein said guide means include two non-circular endless guide tracks respectively located radially inwards of said slide members for guiding the same, said pins, and said vane assemblies.

4. A device as claimed in claim 1 wherein each vane assembly includes an outer part located outward of said control part in radial direction and formed at the radially inner end thereof with a guide recess for guiding said control part.

5. A device as claimed in claim 4 and including spring means in said guide recess abutting said outer part and said control part so that said outer part can move relative to said control part.

6. A device as claimed in claim 1 wherein said endless inner face of said casing member is composed of a plurality of part-cylindrical curved inner face portions; and wherein said guide track means are endless and are composed of a plurality of part-cylindrical curved outer track portions whose radii of curvature and angular positions correspond to those of said inner face portions.

7. A device as claimed in claim 6 wherein said end members of said rotor means include end walls formed with openings; and wherein said control part has end portions projecting from the other parts of the vane assembly through said openings and beyond said end walls in axial direction; and wherein said guide means include two guide tracks located outward of said end walls in axial direction and respectively cooperating with said end portions of said control part for guiding said vane assemblies toward said endless inner face.

8. A device as claimed in claim 1 wherein said control part includes a pin having axially projecting end portions, and wherein said guide means include two non-circular guide tracks respectively located inward of said end portions of said pins of said vane assemblies; wherein each vane assembly includes an inner part guided in the respective slot and a shoe part cooperating with said endless inner face of said casing member; and wherein the central portion of said pin mounts said shoe part on said inner part for angular movement.

9. A device as claimed in claim 8 and including slide members turnably mounted on said end portions of each of said pins and slidably engaging said guide tracks.

10. In a fluid handling device, in combination, casing means including a casing member having a non-circular endless inner face and lateral end faces, and inlet and outlet means for a fluid, rotor means mounted in said casing means for rotation about an axis, and including a central rotor portion located within said endless inner

face and two end members projecting in radial direction from said central rotor portion and having a greater diameter than the same and said endless inner face, said end members having endless lateral peripheral faces being, respectively, located opposite at least portions of said lateral end faces embracing the same in sliding and sealing contact whereby a working chamber for said fluid is formed between said rotor means and said endless inner face of said casing member, said rotor means being formed with a set of slots located in radial planes and extending in axial direction in said central rotor portion and into said end members, said rotor means being formed with an axial bore extending through said central rotor portion and through one of said end members, and at least partly into the other end member, and also formed with at least one recess extending from said central bore in radially outward direction into at least one of said end members; mounting means secured to said casing means and located in said central bore; guide means including a non-circular endless guide track means matching the outline of said endless inner face, said guide means being fixedly mounted on said mounting means and located in said recess; and a set of vane means respectively mounted in said slots for radial movement into and out of said slots for dividing said working chamber into intervane spaces, each vane means including a control part slidably guided on said endless guide track means for guiding said vane means in outer radial direction so that said vane means move along said endless inner face.

11. A device as claimed in claim 10 wherein each end member is formed with a recess projecting from said central bore in outward radial direction; wherein said guide means include two guide portions having non-circular guide tracks matching the outline of said endless inner face, said guide portions being fixed on said mounting means and being respectively located in said recesses; and wherein said control part of each vane means has two end portions respectively located radially outward of said guide tracks and guided along the same.

12. A device as claimed in claim 11 wherein each vane means includes a radially outer part; and wherein said control part is guided in said radially outer part for radial movement and has end portions axially projecting from the same.

13. A device as claimed in claim 12 wherein each vane means includes spring means between said outer part and said control part.

14. A device as claimed in claim 13 wherein said outer part of said vane means has a guide recess; wherein each control part includes a slide part guided in said guide recess, and a pin turnably mounted on said slide part and having end portions projecting from the same and from said outer part and engaging said guide tracks.

15. A device as claimed in claim 11 wherein said control part includes a pin mounted on said vane means for turning movement and engaging said guide track means.
